(57) CLAIM

The ornamental design for a beverage clip, as shown and described.

DESCRIPTION

FIG. 1 is a perspective view of a beverage clip showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a second perspective view thereof; and,

FIG. 9 is a third perspective view thereof.

The broken lines immediately adjacent the shaded areas depict bounds of the claimed design while the rest of the broken lines in the drawings depict portions of the beverage clip that form no part of the claimed design.
